BUTTON

Harry H. Knott, Washington, Iowa, assignor to
 American Pearl Button Company, Washington,
 Iowa, a corporation of Iowa

Application October 9, 1935, Serial No. 44,217

1 Claim. (Cl. 24—102)

An object of my invention is to provide a button characterized by the omission of holes for sewing the button on a piece of cloth or the like and having instead of such holes a plurality of radially extending slots cut inwardly from the peripheral edge of the button blank.

A further object is to provide such slots extending to a depth relatively close to the center of the button whereby when the button is sewed in position the thread will form a pattern adjacent the center of the button and the button will be secured adjacent its center so that the major portion of the button is available for lapsing over the edge of a button hole.

Another object is to provide a button which can be more easily and uniformly colored, this being accomplished by exposing a greater edge area of the button blank to permit more ready penetration of the coloring chemicals into the strata of the blank.

A further object is to provide a button which is more inexpensively and readily manufactured than buttons which have to be drilled with thread holes and one which presents a pleasing appearance when used.

With these and other objects in view my invention consists in the construction, arrangement and combination of the various parts of my device whereby the objects contemplated are attained as hereinafter more fully set forth, pointed out in my claim and illustrated in the accompanying drawing, in which:

Figure 1 is a perspective view of a button embodying my invention.

Figure 2 is a sectional view on the line 2—2 of Figure 1 showing the thread slots in the button.

Figure 3 is a similar view showing a modified form of thread slot.

Figure 4 is a plan elevation of the button showing it sewed in position, the threads forming one style of pattern.

Figure 5 is a sectional view on the line 5—5 of Figure 4.

Figure 6 is a plan elevation showing a modified shape of the button, which however, has the thread slots peculiar to my button construction, this button also being shown as sewed in position with the threads forming another pattern.

Figure 7 is a plan elevation of a button showing a greater number of slots than in Figures 1, 4, and 6; and

Figure 8 is another plan elevation showing a button provided with a fewer number of slots than the ones shown in Figures 1, 4, and 6.

On the accompanying drawing I have used the

reference numeral 10 to indicate generally a button blank. This blank is formed and polished in the usual manner and then provided with a plurality of radially extending slots 12 which are cut to a depth substantially close to the center of the blank 10. The inner ends of these slots may be cut at an odd angle as shown at 14 in Figure 2, or at a right angle as shown at 16 in Figure 3, as desired.

Any number of the slots 12 may be provided and they may be radial or arranged at different angles relative to radii of the blank 10 as desired.

In Figure 4 I have shown the button sewed in position, the threads being indicated at 18 and 20. It will be noted that the thread 20 crosses the thread 18, the threads extending diametrically from the bottom of one slot 12 to the bottom of its diametrically opposite slot.

In Figure 5 a piece of fabric 22 is illustrated, the button being sewed to this fabric and this figure serving to illustrate how the thread passes through the slots instead of through thread holes in the usual manner.

In Figure 6 I show a button blank 10a. The shape of this blank is somewhat modified with respect to the shape shown in Figure 1 and it is illustrated as being sewed in position by threads 18a and 20a. The threads, it will be noted, instead of being crossed as in Figure 4, extend in a box-like formation, thus creating a different appearing design of the thread and button in conjunction with each other.

It is therefore evident that the button is adaptable to various shapes and it is thereby possible to produce different distinctive designs when the button is sewed in position.

In Figure 7 I show a button blank 10b having six thread slots 12b instead of four as shown in Figure 1.

In Figure 8 I show a button blank 10c with only three thread slots 12c. Blanks in the buttons of Figures 7 and 8 are illustrated sewed in position, the threads forming respectively a six spoke and triangular design.

My button is easy and inexpensive to manufacture as it does away with the drilling machines and drilling operations heretofore used in connection with the manufacture of buttons and utilizes instead saws or the like which are of more sturdy construction and less subject to breakage than the thread hole drills now in use.

Also in sewing the button in position, it is a comparatively easier matter to find the slot-like thread opening of my button with the point of a

needle than it is to find a comparatively small thread hole as now in general use. Thus the slots 12 are an improvement both from the manufacturer's and user's standpoints.

5 Some changes may be made in the construction and arrangement of the parts of my device without departing from the real spirit and purpose of my invention and it is my intention to cover by my claim any modified forms of structure or
10 use of mechanical equivalents which may be reasonably included within its scope.

I claim as my invention:

A button comprising a blank having substantially level and parallel front and back faces and a plurality of thread slots cut into the peripheral edge thereof to a depth relatively close to the 5 center of the blank, the inner ends of said slots being inclined downwardly and outwardly from the front face of said blank.

HARRY H. KNOTT. 10
